UNITED STATES PATENT OFFICE.

FRED W. HERRMANN, OF ATLANTIC, IOWA.

HARROW-TOOTH HOLDER.

SPECIFICATION forming part of Letters Patent No. 289,260, dated November 27, 1883.

Application filed June 15, 1883. (No model.)

To all whom it may concern:

Be it known that I, FRED W. HERRMANN, a citizen of the United States, residing at Atlantic, in the county of Cass and State of Iowa, 5 have invented certain new and useful Improvements in Harrow-Tooth Holders; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to improvements in harrow-tooth holders; and it consists in the combination and arrangement of the several parts, hereinafter fully described, and specifically pointed out in the claims.

20 In the drawings, Figure 1 is a top or plan view of a part of one of the harrow-bars, showing the fastening-nuts on the ends of the retaining-bolts. Fig. 2 is a side elevation of a harrow-bar, a tooth-holder fixed thereto, and

25 of the tooth suspended in the holder. Fig. 3 is a view of the under end of the holder. Fig. 4 shows a view of the upper end and a side elevation of the holder. Fig. 5 shows a side view and an edge view of one of the harrow-teeth. Fig. 6 is a vertical section of one of the harrow-bars and of a tooth-holder, showing the tooth in position. Fig. 7 shows a tooth having a rectangular head, and Fig. 8 shows a vertical section of a tooth-holder and harrow-bar, and the tooth reversed from the position

30 shown in Fig. 6, whereby the said tooth is locked or held rigidly in a vertical position.

35 *a* is the harrow-bar, to which the tooth-holder is held by bolts *a'* and nuts *a''*, as shown.

40 *b* is the holder, which is elongated, as shown, and has formed vertically through it the tooth-opening *b'*. The tooth-opening is made preferably oval in shape, as shown, and has its front point or wall, *b''*, arranged on a vertical line, and its rear point or wall, *b'''*, flared, as shown, so as to permit the tooth to swing back to the angle commonly given to inclined teeth in harrows. A recess or mortise, *b''*, is formed 45 in the top of the holder, and surrounding the upper end of the opening or socket *b'*. This

55 mortise is made preferably wider than the upper end of the opening *b'*. It is, however, not necessary to make it so. It may be of same width with the mortise; but it should be preferably a little longer, for purposes herein-after set forth. The bottom of the mortise is on a line or plane transverse to the tooth socket or opening *b'*. The socket is deep enough to receive the head of the tooth, hereinafter described. The holder is provided with perforated lugs *b''* *b'''*, arranged at opposite ends, as shown, and through them the retaining-bolts *a'* are put in the manner shown. The lugs *b''* are not arranged in line with the longest 60 diameter of the tooth-socket *b'*, but laterally thereto, the one on one side thereof, the other on the other side thereof. This lateral arrangement permits the lugs to be set in line with the harrow-bar *a*, and the setting of the 65 latter to an incline to or across the line of motion of the harrow, and at the same time preserve the longest diameter of the socket *b'* directly in line with the direction of motion.

70 *c* is the tooth, preferably oval in form, to adapt it to the shape of the opening *b'*, and so that it will present its edge in the direction of the movement of the harrow. A head, *c'*, is formed on the tooth, and is adapted to enter 75 the mortise *b''* in the holder *b*, and project past the ends of the oval-shaped opening or socket. The head *c'* may be made to set at a right angle to the tooth, or it may be set at an inclined angle thereto, as shown. I prefer to set it at 80 the inclination shown, because when it is reversed, as shown in Fig. 8, it becomes locked in its position—a result that would not be attained were the head projected at right angles. The head is preferably made in the form 85 shown in Fig. 5, where the upper and under faces are formed in the arc of a circle. This form rocks more freely and gives better results, though very excellent results are derived when the head is made in the form 90 shown in Fig. 7, or is set at a right angle to the stem of the tooth.

95 The operation of the device is clearly illustrated in Figs. 6 and 8. The head tilts on one end to permit the tooth to turn back, as shown 100 in dotted lines, Fig. 6, while the other end of the head is elevated and touches the harrow-

bar and prevents the tooth from being pushed upward. When the tooth drops to the vertical position, the opposite end of the head touches the harrow-bar, as shown in full lines, Fig. 6. 5 By reversing the position of the tooth, as shown in Fig. 8, the highest end of the head touches the bar, and the tooth will be locked in a vertical position. When the tooth is provided with a head made at right angles thereto there will be a slight vertical movement of the tooth when it is used in a vertical position. It would make a slight noise, caused by this sliding movement; but the general action is the same as that where the head is set 15 at an incline. I prefer the setting of the head on an incline, as hereinbefore described.

The harrow-body to which my improved tooth is attached is so constructed that it may be drawn in either direction—that is, it is provided with hitching devices on its forward and on its rear end. When a slant tooth is desired, the team is hitched to one end, and when a straight tooth is desired the team will be hitched to the other end.

25 I am aware that harrow-tooth holders have heretofore been made with one vertical and one inclined wall, and the teeth have been secured in said holders, so they may be moved to bear against one or the other of said walls. 30 I do not claim this, broadly, as my invention; but,

Having described my invention, what I claim, and desire to secure by Letters Patent, is—
1. A harrow-tooth holder provided with 35 means for attaching it to the beam or tooth-bar of a harrow, and having a vertical oblong socket through the holder, with one of its walls straight and the opposite wall inclined from its upper end outward and away from the 40 straight wall, and having in its upper face an oblong mortise leading from the upper end of the socket, and adapted to receive the head of the tooth and permit the tilting or rocking of said tooth-head, substantially as set forth.
45 2. A harrow-tooth holder having a vertical oblong socket or opening through it, with one

of its walls straight and the opposite wall inclined, and having in its upper face a longitudinal mortise leading from the ends of the oblong socket, in combination with a harrow-tooth having an oblong head adapted to be placed in the longitudinal mortise and tilt upon its ends, as and for the purposes set forth. 50

3. The combination of the harrow-bar, the harrow-tooth holder having a vertical oblong 55 socket through it, with one of its walls straight and its opposite wall inclined, and having in its face a longitudinal mortise leading from the oblong socket, and the tooth having an oblong head curved upon its upper and under 60 faces, and adapted to be placed in the oblong mortise and tilt upon its ends, substantially as set forth.

4. A harrow-tooth holder having a vertical oblong socket or opening through it, with one 65 of its walls straight and its opposite wall inclined, and having in its upper face an oblong mortise leading from the ends of the oblong socket, in combination with a harrow-tooth having an oblong head set at an incline to the 70 body of the tooth and adapted to tilt within the oblong socket, substantially as and for the purposes set forth.

5. A harrow-tooth holder having a vertical oblong socket formed through it, with one of 75 the walls of the socket straight and the opposite wall inclined, and having in its upper face an oblong mortise leading from the ends of the oblong socket, in combination with a reversible tooth having an oblong head set at an 80 incline to the body of the tooth and adapted to be placed within the oblong socket and tilt upon its end, or be reversed and locked between the tooth-bar and the bottom of the mortise, substantially as and for the purposes 85 set forth.

In testimony whereof I affix my signature in presence of two witnesses.

FRED W. HERRMANN.
